SEQUENCE SWITCH DEVICE

David W. Johnson, New Britain, Conn., assignor
to The Arrow-Hart & Hegemann Electric Com-
pany, Hartford, Conn., a corporation of Con-
necticut

Application April 1, 1946, Serial No. 658,621

16 Claims. (Cl. 200—5)

1

This invention relates to electric switch mechanisms or, more particularly, to electric switch mechanisms for operating a series of switches or switch contacts in sequence to carry out a predetermined plan or program in an electric circuit.

It is an object of this invention to provide a mechanism for operating several electric switches or switch contacts in sequence to carry out a program, and to require completion of the program by said sequential operation before any permanent position of the device can be achieved.

Another object of the invention is to provide for reversing the sequence in a switch of the foregoing type, and to require a complete reversal of the sequence before any previous permanent position of the device can be reestablished.

Another object is to provide a mechanism for achieving the foregoing objects in which the program may be carried out at any desired regular or irregular rate.

Another object is to provide a mechanism for achieving the foregoing objects, which returns itself to the beginning of any sequence on which it has been started if that sequence (whether an initial or a reversal of a previous sequence) is not carried to completion.

Other objects and advantages of the invention will appear as it is described in the accompanying drawings.

In the drawings—

Fig. 1 is a side elevation view of the invention; Fig. 2 is a transverse section view of the invention illustrated in Fig. 1, the section being taken along line 2—2 of Fig. 1;

Fig. 3 is a bottom plan view of the invention;

Fig. 4 is a transverse section view of the invention, the section being taken along line 4—4 of Fig. 6 with the parts advanced toward a new position;

Fig. 5 is a transverse section view of the invention, the section being taken along line 5—5 of Fig. 6;

Fig. 6 is a fragmentary elevation view partly in section of the invention illustrated in Fig. 1;

Fig. 7 is a view similar to Fig. 4 with the parts still further advanced toward a new position, and

Figs. 8, 9 and 10 are detailed perspective views of three parts of the operating mechanism.

Referring to the drawings, a pair of rectangular parallel metal plates 20 and 22 have mounted between them four electric switches 24, 26, 28 and 30. Any suitable securing means, such as bolts 32 passing through the top plate 20 and through the casings of the switches and threading into 55

2

the bottom plate 22, may be employed to secure the plates and switches in fixed relation. In the form of the invention illustrated, the switches 24, 26, 28 and 30 are switches which are operated by a very slight degree of movement of their operating members, i. e. 25, 27, 29, 31. Such switches per se form no part of the present invention and therefore no detailed description of the structure and operation need be given. Generally, such switches are housed in a rectangular or prismatic casing of molded insulation having an opening in one side for a spring-biased operating plunger or cam member (such as 25, 27, 29, 31) which causes engagement and disengagement of separable contacts (not shown); and terminals (such as 33, 34) extend from opposite ends of the casing for connection of the circuit wires.

The operation of the contacts within the individual switches 24, 26, 28 and 30 may be the same or different. That is, they may be normally open or normally closed, or otherwise. Such switches are commonly made both ways, and also, commonly, closed in both actuated and unactuated position.

For operating the switches 24, 26, 28 and 30 a spindle 42 carrying cam discs 35, 37, 39, 41 which rotate therewith is mounted in bearing apertures in the plates 20 and 22 between the two stacks of switches 24, 26 and 28, 30. The cam discs may be stamped from sheet insulation with one or more high points, for example 35a, 41a and may be spaced and located along the spindle by insulating spacing washers 44 so that the high points of the cam discs 35, 37, 39 and 41 will, in any desired order or sequence, engage the switch operators 25, 27, 29, 31 respectively to actuate their individual switches.

If desired, one or more of the cam discs may be provided with two high points so as to operate two of the switches by engaging the operating members of both switches. It will be readily understood by those skilled in the art that the order of operation and the number of times that any of the four switches 24 and 26 and 28 and 30 are caused to operate by the operating cams during rotation through a predetermined angle will depend upon the conditions and circumstances required for its use in any particular circuit.

Although in the form of the invention illustrated, the cam discs are maintained in position axially upon the spindle 42 by stacks of small insulating washers or discs 44, obviously the cams and spacers might be molded as one part if a one-piece construction were desired.

For manually operating the spindle 42 and

thereby causing rotation of the cam discs, a handle 46 may be provided on the end of the spindle. From the foregoing it will be obvious that upon turning the handle 46 the switches will be caused to operate, by rotation of the several cam discs, in a predetermined sequence to carry out a program.

In order to insure that the program is carried out according to the predetermined plan or sequence and also to insure that if the program is not carried out completely, the switch spindle and parts carried thereby will return to the position from which the spindle was started on its turning movement, I have provided a position-maintaining mechanism on the bottom or outside of the plate 22. This mechanism is operated by and in part mounted upon an extension of the spindle 42 beyond the bottom or outside surface of the plate 22.

An operating member, designated generally by the numeral 50, is stamped from sheet metal into substantially U-shape, as best shown in Fig. 8, with one plate 52 thereof lying against the bottom surface of the mounting plate 22 and sliding thereover as the switch spindle is rotated. The other or opposite side plate 54 of the member 50 comprises a central disc portion from which radial extensions 56 and 58 are bent up parallel to each other to receive a bifurcated key or securing member 48, one end of which extends through a rectangular opening 57 stamped in the extension 56 while the other or bifurcated end has its tines extending through a pair of openings 59 stamped in the opposite extension 58. The bifurcations of the key embrace the end of the spindle 42 and fit into flats cut in opposite sides of the spindle 42 near its end. Both side plates of the operating member 50 are apertured to receive the spindle on which the operating member 50 is non-rotatably mounted.

Between the plates 52 and 54 of the operating member 50 is located a spring cage member (designated generally by the numeral 60) which is stamped from sheet metal and bent into U-shape, in the form best illustrated in Fig. 9. One side plate 62 of the member 60 is in the form of a disc having a central aperture for the passage of the spindle 42. The other or opposite side plate 64 of the member 60 is also in disc form with a wide radial extension providing shoulders 65 and 67 for engagement with a sliding latch member (designated generally by the numeral 70) as will hereinafter be more fully described.

Between the plates 62 and 64 of the spring cage member 60 there is a spiral spring 80 which has radially extending ends 82 and 84 embracing and engaging the opposite sides of the U or connecting portions of both the spring cage member 60 and the operating member 50. The spring ends thus tend to maintain the U-portions in register.

The latch 70 may be stamped from sheet metal into the form best illustrated in Fig. 10 and it may comprise a flat plate portion 72 lying upon and slideable over the outer or bottom surface of the plate 22. The latch is slidably held by pins 78, 78' which pass through elongated apertures 73, 74 of the member 70. An arcuate bar portion 75 is bent up perpendicular to the surface of the member 70 at one edge in position to have its ends engaged by one shoulder or the other 65 or 67 of extension 66 of the spring cage member 60 and to thus hold that member against rotation. To press the latch 70 toward the cage member 60 so that the latch bar 75 will normally be in position

to be engaged by one or the other of the shoulders 65, 67 of the cage extension, a wire spring 71 is wound around the pins 78, 78' with its mid-portion engaging the back of the latch bar 75.

In order to move the latch 70 and disengage latch bar 75 from whichever of the shoulders 65 or 67 it is then engaged with, cam surfaces 53 and 55 are formed on the plate 52 of the operating member 50; and cam surfaces 76 and 77 are formed on the inner surfaces of opposite end portions of the latch member 70, in position for the cam surface 53 of the operating member to press against cam surface 76 of the latch when the operating member is moved counterclockwise from the position of Fig. 4, or for the cam surface 55 to press against cam surface 77 when the operating member is moved from the position of Fig. 5 into the position of Fig. 4, as more fully explained below.

Operation.—The extension 66 on the member 60 lies on one side or the other of the arcuate latch bar 75 when the parts are at rest. Assuming the parts in the position of Fig. 3, when the operating member 50 is rotated by turning the spindle 42 counterclockwise, the U-portion 51 of that member engaging the end 84 of the spring will stress the spring still further (the spring being initially provided with some tension or stress) until the parts are in the position of Fig. 4. In the meantime, the spring cage member 60 has been held stationary by its shoulder 67 engaging the arcuate latch bar 75.

Thereupon the cam portion 53 of the operating member 50 engages the cam portion 76 of the latch member 70 moving member 70 and with it the arcuate latch bar 75 against the urge of spring 71 away from shoulder 67 of the member 60. This releases the member 60. Since at that time the other end 82 of the spring 80 is urging the spring cage member 60 counterclockwise (in Fig. 4) the force of the spring will cause the spring cage member to rotate in counterclockwise direction until the U-portion of the cage member 60 is in register with the U-portion of the operating member 50 with the ends of the spring 80 on opposite sides of these U-portions, in which position the parts will be at rest and in equilibrium.

It is not possible to move the spindle 42 further in counterclockwise direction from this new position because the cam portion 53 of the operating member 50 abuts the cam portion 76 of the latch member to prevent movement (see Fig. 7).

From the new position just described the parts 55 can be reversely rotated with an action just opposite of that described. Thus, the clockwise rotation of the operating spindle will cause clockwise movement of the operating member 50 causing its U-portion to engage the end 82 of the spring while the spring cage member remains stationary due to the engagement of shoulder 65 with the arcuate latch 75. Ultimately cam surface 55 of the operating member will engage the cam surface 77 of the latch member 70 and will move the arcuate latch bar 75 out of engagement with the shoulder 65 of the spring cage member for clockwise rotation under the urge of the spring, whereupon the parts will return to the position illustrated in Fig. 3. Further rotation in a clockwise direction is prevented by the cam surface 55 on the operating member 50 engaging the cam surface 77 on the latch member.

It may be readily understood from the foregoing that each rotation of the spindle 42 will cause conjoint rotation of the operating cam discs

35, 37, 39 and 41 and operation of the switches 24, 26, 28 and 30 according to the predetermined sequence; but unless the sequence is completed, the spring 80 will cause reverse rotation of the spindle 42 as soon as the handle 46 is released. Therefore the spindle will return to the position from which it was started on the rotating movement, and the one or more of the switches which may have been operated by the cam discs will be released or again operated to disestablish the conditions which had been established by the partial completion of the sequence. Thus the switch will be back in its initial or starting position. On a new start of rotation, the spindle 42 will start again from the beginning of its sequence. If the sequence is completed then the mechanism beneath plate 22 will have operated in the manner above described and will remain at rest in a new position at the end of the sequence to hold the operating spindle there.

In similar manner on reverse rotation of the operating spindle, complete reversal will be necessary before the condition established by the operation of the switches 24, 26, 28 and 30 will be maintained. Only upon completion of the series, in forward or in reverse order as the case may be, is the mechanism beneath plate 22 operated in the manner above described; and only upon such operation can the parts remain stationary after return to their original position, for example the position of Fig. 3.

The spindle 42 may be operated at any desired rate or may be held in a partially completed position by hand in case it is desired to maintain the conditions established by partial completion of the sequence temporarily. However, if such temporary hand control is released the device will immediately return to its initial position. Thus, it is necessary after such momentary slowing down or holding of the switch in a partially completed sequential position that the remainder of the sequence be completed in the manner described before the parts may be maintained in a stationary position.

Many modifications within the scope of my invention will occur to those skilled in the art and therefore I do not limit my invention to the specific form or embodiment of the invention herein disclosed.

I claim:

1. An electric switch comprising a rotary spindle, a plurality of switch contacts operated in a predetermined sequence as said spindle is turned, spring means operable to return the spindle to its starting position if the sequence is not completed, and means including said spring means operable on completion of operation of said contacts through said sequence to maintain the spindle in sequence-completed position.

2. An electric switch comprising a rotary spindle, a plurality of switch contacts operated in a predetermined sequence as said spindle is turned, spring means operable to return the spindle to its starting position if the sequence is not completed, and means including said spring means operable on completion of operation of said contacts through said sequence to maintain the spindle in sequence-completed position, said spindle being operable in reverse direction from said sequence-completed position to operate said contacts in reversed sequence, and said spring means acting to return said spindle to sequence-completed position if said reverse-sequence is not completed, said maintaining means operating on completion of

said reverse-sequence to maintain its initial position.

3. An electric switch comprising a rotary spindle, a plurality of switch contacts operated in predetermined sequence as said spindle is turned, means to manually operate said spindle, means tending to maintain said spindle in a stationary position and tending to return said spindle to said position during the continuance of said sequential operation, and latching means released upon the completion of said sequential operation of said plurality of contacts and thereupon permitting maintaining means to move into a new sequence-completed position for maintaining said spindle in said new position.

4. An electric switch comprising a rotary spindle, a plurality of switch contacts operated in predetermined sequence as said spindle is turned, means to manually operate said spindle, means tending to maintain said spindle in a stationary starting position, said maintaining means moving into a sequence-completed position after a predetermined movement of said manually operated means, and latching means preventing said maintaining means from taking said sequence-completed position until the manually operated means has operated said plurality of switch contacts and completed said predetermined movement.

5. An electric switch comprising a rotary spindle, a plurality of switch contacts operated in predetermined sequence as said spindle is turned, means to manually operate said spindle, means tending to maintain said spindle in a stationary sequence-starting position, said maintaining means moving into a completed position after a predetermined movement of said manually operated means, and latching means preventing said maintaining means from taking said sequence-completed position until the manually operated means has operated said plurality of switch contacts and completed said predetermined movement, said latching means being released by said manually operated means after said predetermined movement.

6. An electric switch comprising a rotary spindle, a plurality of switch contacts operated in predetermined sequence as said spindle is turned, means to manually operate said spindle, means including a spring biasing and tending to maintain said spindle in a stationary sequence-starting position, said maintaining means moving into a sequence-completed position after a predetermined movement of said manually operated means, and latching means preventing said maintaining means from taking said sequence-completed position until the manually operated means has operated said plurality of switch contacts and completed said predetermined movement.

7. An electric switch comprising a rotary spindle, a plurality of switch contacts operated in predetermined sequence as said spindle is turned, means to manually operate said spindle, means tending to maintain said spindle in a stationary starting position, said maintaining means moving into a sequence-completed position after a predetermined movement of said manually operated means, and latching means preventing said maintaining means from taking said sequence-completed position until the manually operated means has operated said plurality of switch contacts and completed said predetermined movement, said manually operable means being operable in clockwise and counter-

clockwise directions from one or the other of said sequence-starting or sequence-completed positions to complete the sequence in forward or reverse directions.

8. In an electric switch, switching means comprising a plurality of switch contacts, means including a rotary shaft for manually operating said contacts in a predetermined order, in combination with means tending to maintain said operating means in sequence-starting position, and means to return said operating means to said position if the sequence is not completed, and means to hold said operating means in sequence-completed position on completion of the sequence.

9. In an electric switch, switching means comprising a plurality of switch contacts, means including a rotary shaft for manually operating said contacts in a predetermined order, in combination with mechanism tending to maintain said operating means in sequence-starting position, to return said operating means to said position if the sequence is not completed and to hold said operating means in sequence-completed position on completion of the sequence, said mechanism comprising an operating member moving conjointly with said shaft, spring means tensioned by movement of said operating member, a movable member affording one anchor for said spring means, latching means holding said anchor member, said latching means being released by said operating member on completion of the sequence.

10. In an electric switch, switching means comprising a plurality of switch contacts, means including a rotary shaft for manually operating said contacts in a predetermined order, in combination with mechanism tending to maintain said operating means in sequence-starting position, and to return said operating means to said position if the sequence is not completed, and to hold said operating means in sequence-completed position on completion of the sequence, said mechanism comprising an operating member moving conjointly with said shaft, spring means tensioned by movement of said operating member, a movable member affording one anchor for said spring means, latching means holding said anchor member, rotation of said operating member in one direction causing release of said latching means on completion of the sequence and causing release of said latching means on completion of reverse sequence when said operating member is rotated in the reverse direction.

11. In an electric switch, switching means comprising a plurality of switch contacts, means including a rotary shaft for manually operating said contacts in a predetermined order, in combination with mechanism tending to maintain said operating means in sequence-starting position, to return said operating means to said position if the sequence is not completed and to hold said operating means in sequence-completed position on completion of the sequence, said mechanism comprising spring means, a pair of rotary members affording anchors for the ends of said spring means, one of said members moving in direct response to movement of said manual operating means, a latch member biased in position to hold the other of said pair, said latch member being engaged and moved from said holding position by the first of said pair on completion of the sequential operation.

12. In an electric switch, switching means comprising a plurality of switch contacts, means

including a rotary shaft for manually operating said contacts in a predetermined order, in combination with mechanism tending to maintain said operating means in sequence-starting position, to return said operating means to said position if the sequence is not completed and to hold said operating means in sequence-completed position on completion of the sequence, said mechanism comprising spring means, a pair of rotary members affording anchors for the ends of said spring means, one of said members moving in direct response to movement of said manual operating means, a latch member biased in position to hold the other of said pair, said latch member being engaged and moved from said holding position by the first of said pair on completion of the sequential operation, said spring means tending to return said operating means to sequence-starting position until completion of the sequence, and operating upon such completion to maintain said pair in sequence-completed position.

13. In an electric switch, switching means comprising a plurality of switch contacts, means including a rotary shaft for manually operating said contacts in a predetermined order, in combination with mechanism tending to maintain said operating means in sequence-starting position, to return said operating means to said position if the sequence is not completed and to hold said operating means in sequence-completed position on completion of the sequence, said mechanism comprising spring means, an operating member having an arm engaged on opposite sides by the ends of said spring means, a spring anchor member having an arm engaged on opposite sides by said spring ends and normally maintained thereby in register with said first arm, a slidable latch member biased to restrain movement of said anchor member during movement of the operating member toward sequence-completed position, said latch member and said operating member having cam surfaces engaging at the completion of the sequence to release said anchor member and bring its arm into register with said operating arm in sequence-completed position.

14. In an electric switch, switching means comprising a plurality of switch contacts, means including a rotary shaft for manually operating said contacts in a predetermined order, in combination with mechanism tending to maintain said operating means in sequence-starting position, to return said operating means to said position if the sequence is not completed and to hold said operating means in sequence-completed position on completion of the sequence, said mechanism comprising spring means, an operating member having an arm engaged on opposite sides by the ends of said spring means, a spring anchor member having an arm engaged on opposite sides by said spring ends and normally maintained thereby in register with said first arm, a slidable latch member biased to restrain movement of said anchor member during movement of the operating member toward sequence-completed position, said latch member and said operating member having cam surfaces engaging at the completion of the sequence to release said anchor member and bring its arm into register with said operating arm in sequence-completed position, said operating member being operable in one direction to complete the sequence and to cause movement of the spring and anchor members into sequence-completed position and operable in reverse direc-

tion to reverse the sequence and cause movement of the spring and anchor members and contacts into sequence-starting position.

15. An electric switch as claimed in claim 11 wherein the pair of rotary members, spring means and latch member are constructed and arranged to operate in both forward and reverse directions in the same manner.

16. An electric switch as claimed in claim 12 wherein the pair of rotary members, spring means and latch member are constructed and arranged to operate in both forward and reverse directions in the same manner.
